GOLF CLUB CARRIER FOR ATTACHMENT TO A GOLF CART

Isao Sasaki, Pasadena, Calif.

Application May 1, 1959, Serial No. 55,733

Term of patent 3½ years

(Cl. D34—5)

Des. 186,715

PAGE 2

FIG. 3.

FIG. 4.

Fig. 1 is a front elevation of a golf club carrier for attachment to a golf cart showing my new design;

Fig. 2 is a side elevational view thereof;

Fig. 3 is a top plan view thereof;

Fig. 4 is a plan section taken along line 4—4 of Fig. 1; and

Fig. 5 is a fragmentary plan section taken along line 5—5 of Fig. 1.

I claim:

The ornamental design for a golf club carrier for attachment to a golf cart, as shown.
